PRESSING SOLES

Application filed December 10, 1926. Serial No. 153,968.

This invention relates to sole pressing machines and methods and is herein disclosed by reference to a leveling machine of the so-called "direct pressure" type, such as is shown generally in the United States Letters Patent No. 581,662, granted April 27, 1897, on the application of John J. Heys. The invention is not, however, to be understood as limited to leveling machines of this type, nor indeed to leveling machines or methods alone, many of the advantages of the invention being obtainable, for example, in the use of sole laying or molding machines.

Leveling machines of the type mentioned ordinarily comprise two primary pressure imparting members which are moved relatively toward each other by a power mechanism, as for example, a cam or a crank shaft, or a toggle mechanism connected with one of them, to apply pressure to a sole held between them. The sole is, in general, held on a leveling last or form mounted on one of the members and supporting the inside face of the sole, and the other member carries a complementally shaped outer-face-pressing form co-operating with the first-named form under pressure of a spring located between the primary pressure imparting members to shape the sole. It has never been possible in such machines to secure uniform pressure per square inch upon soles of different sizes without resorting to impractical procedure in regard to adjustment to each size of sole. The distance between the primary pressure imparting members at the time of maximum pressure is invariable except as modified by such adjustment, and the total pressure applied to the sole is proportional to the compression of the spring and is therefore substantially constant for shoes of a given style unless the machine is adjusted for each size of shoe. A #2 sole is about 17 square inches in area and a #8 sole is about 24 square inches in area, and this results in a considerably less pressure per square inch upon the larger sole than

upon the smaller. While machines have included heretofore means for adjustably varying the amount of pressure, operators cannot always be depended upon to make the adjustment in changing from one size to another, 50 and moreover there has been no definite way of determining how much adjustment was required.

In view of the above and other considerations, the present invention provides a novel 55 method and novel means whereby the proper amount of pressure per unit of area is insured without preliminary adjustment. In accordance with the novel method, in one aspect, there is utilized, for leveling or pressing soles 60 of each different size and surface area, a different spring-controlled sole-pressing form of a thickness proportional to the size of the sole, to cause correspondingly different amounts of stress of the spring such as to produce substantially the same unit pressure in operating on the different sized soles. As a part of a 65 novel machine organization, the invention provides, for operating on a given sole, a form having sufficient thickness to effect such 70 additional compression of the spring, as compared with a form of less thickness corresponding to the area of a smaller sole, as to apply to the given sole substantially the same 75 pressure per unit of area as would be applied by the thinner form to the smaller sole. The desired uniformity in the amount 80 of pressure applied is accordingly secured without any labor or care on the part of the operator other than that involved in the customary changing of the forms for soles of different sizes.

The invention in its novel method and machine aspects will now be more particularly 85 described by reference to the accompanying drawings and pointed out in the claims.

In the drawings—

Fig. 1 is a side elevation of the machine;

Fig. 2 shows four sets of forms and the 90

corresponding shoes increasing in size from left to right; and

Fig. 3 shows the outlines of the four soles treated in the apparatus of Fig. 2.

5 The machine of Fig. 1 will in its general aspects, be found fully described in the patent above referred to. It comprises a primary pressure imparting member or table 10 on which is mounted the so-called lower 10 form 12 and which is forced vertically toward the so-called upper form 14 by a cam 16 which is rotated about a vertical axis. The high point of this cam always raises the table 10 to the same point, and the low point drops 15 it down to permit change of work. The upper form 14 is supported on the end of a plunger 18 which is resiliently pressed downward by a very heavy spring 20, housed in the head of the frame. The upper abutment 20 22, the other primary pressure imparting member, is adjustable by a screw 24. The forms 12 and 14 are made of metal and are shaped complementarily to conform to the shape desired on the shoe bottom. In view 25 of the confusion resulting from the terms "lower" and "upper" because of the inversion of the shoe, these forms will be herein called "inner" and "outer" respectively, though no limitation is thereby intended to the treatment 30 of a sole already on a shoe, the invention being useful in the treatment of unattached soles.

The total pressure on the shoe depends on the compression of the spring 20. Prior to 35 the present invention, the combined height of the forms 12 and 14 has always been uniform for all sizes. Thus the bottom end of the plunger 18 was always raised to the same point, and the spring would be compressed 40 to the same extent in treating all shoes unless the compression were relieved for the small shoes by adjusting the abutment 22. Operators frequently neglected this with the result that the large shoes got too little pressure 45 or the small ones too much, and the smaller inner forms were often broken. Moreover, operators had no definite knowledge of the amount of adjustment needed to give uniform pressure on soles of different 50 sizes.

The present invention avoids this difficulty by varying, as herein illustrated, the combined thicknesses of the forms and the consequent spring distortion to control the total 55 pressure on soles of different sizes without adjustment by the operator. The spring 20 used in the disclosed machine was carefully calibrated and found to have a coefficient of distortion of about 11 tons per inch of compression. The areas of a standard set of soles were measured, and the thicknesses of the combined form-pairs were so arranged as to secure substantially uniform unit pressure on all soles, irrespective of the areas, 60 65 without adjustment or care by the operator.

It was found that in order to get the desired pressure of about 550 pounds per square inch, on this set of soles, the spring required an additional compression of 1/32 inch per unit increase in size of shoe.

70 This was arrived at as follows: The #2 sole had about 16.59 square inches area, and the #8, about 23.89 square inches. The increase therefore was about 1.22 square inches per size. The increment of pressure was 75 therefore about

$1.22 \times 550 = 670$ pounds
and the change in length of the spring required to produce this pressure was

$$\frac{670}{21800} = .031 \text{ inch.}$$

80 This grading was all put into the outer forms in the disclosed apparatus. Thus, when the proper pair of forms for a shoe is put in the machine, it automatically takes care of the pressure.

85 Four such pairs of forms are shown in Fig. 2. The increase in thickness of the form pairs has been grossly exaggerated for the 90 sake of clearness in disclosure.

Having described the invention, what we claim as new and desire to secure by Letters Patent of the United States is:

95 1. A sole-pressing machine having a pair of pressure-applying forms and a pressure mechanism comprising a spring arranged to force the forms relatively toward each other with a sole between them, the pair of such forms having sole-engaging areas to operate upon a sole of a certain area, one of said forms having sufficient thickness to provide it with a portion to effect such additional compression of the spring during the operation of the machine as to cause the machine, 100 without preliminary adjustment, to apply to such sole substantially the same pressure per unit of area as would be applied to a sole of less area when operated upon by such machine provided with a form of correspondingly less thickness.

105 2. That improvement in methods of leveling or pressing soles of varying sizes and surface areas which consists in subjecting the soles to pressure between sole-engaging 110 forms, one of which is backed by a spring, and causing said forms to apply substantially the same pressure per unit of area to soles of different sizes and surface areas by varying the total thickness of the forms in proportion to the areas of the soles being operated upon.

115 3. That improvement in methods of subjecting soles of varying sizes and surface areas to substantially the same leveling pressure per unit of area which consists in utilizing, for leveling soles of each different size and area, a different spring-controlled sole-pressing form of a thickness proportional to the size of the sole, to cause correspondingly 120 125 130

different amounts of stress of the spring such as to produce substantially the same unit pressure in operating on the different sized soles.

5 In testimony whereof we, the said LUCY A. HEYS and GEORGE H. HEYS, have signed our names to this specification.
